To all whom it may concern:

Be it known that I, JACOB M. HEASLEY, a citizen of the United States, residing at Pittsburgh, in the county of Allegheny and State of Pennsylvania, have invented and produced a new and useful Design for Envelops, of which the following is a full, clear, and exact description, reference being had to the accompanying drawings, forming part of this specification, in which—

My invention relates to a design for an envelop.

The leading features of my design reside in the indentations 2 and the patches 3 on one face of the envelop.

I claim—

The design for an envelop as shown and described.

In testimony whereof I have hereunto set my hand.
